JOSEPH B. TEDROW, OF CHILLICOTHE, OHIO.

Letters Patent No. 87,729, dated March 9, 1869.

IMPROVEMENT IN FENCES.

The Schedule referred to in these Letters Patent and making part of the same.

To all whom it may concern:

Be it known that I, JOSEPH B. TEDROW, of Chillicothe, in the county of Ross, and State of Ohio, have invented certain new and useful Improvements in Fences; and I do hereby declare that the following is a full, clear, and exact description thereof, which will enable those skilled in the art to make and use the same, reference being had to the accompanying drawings, forming part of this specification.

This invention relates to improvements in fences, the object of which is to render them cheaper of construction, more durable, and to arrange them so that they may be protected from floods, when located in river-bottoms subject to be overflowed.

It consists in providing sectional posts, to be constructed partly or wholly of metal, and joining the sections by hinging them together.

Figure 1 represents a side elevation of one panel of a fence, constructed with my improved posts.

Figure 2 represents edge views of the posts.

Similar letters of reference indicate corresponding parts.

I purpose to construct the posts partly of iron and wood, and in sections, and sometimes wholly of iron.

For fences to be used on low river-bottoms, that are subject to be overflowed, I purpose to construct the posts in two parts, A and B, and hinge the two parts together with a double joint, as represented at C, and make the pintle of the up-stream side of wood, so that if the water rises suddenly, and without sufficient warning to admit of their being withdrawn, they will break,

and allow the fence to swing down to present only an edgewise resistance to the current.

After the water has subsided, they may be raised up again, and the joints fastened as before.

The part B may be made of cast-iron, and of wedge-form, so as to be driven readily into the earth.

The part A may either be made of wood or metal, as preferred.

If made of iron, the cross-pins *a* may be cast with the other portion, and the transverse slots *b* may be made in them, to save metal, and to allow a free circulation of air for the ends of the boards or rails.

D represents the form of post which I prefer for the middle posts, as possessing the greatest amount of strength with the least amount of metal.

The boards or rails for the top joint may be tapered at the ends, as represented at *E*, so as to lap each other, and may be joined together by pins, or nails, *F*.

I claim as new, and desire to secure by Letters Patent—

1. Fence-posts, made in sections A and B, and hinged together, substantially as and for the purpose described.

2. The hinged section A, formed with the supporting-rods *d* and the openings *b*, substantially as and for the purpose described.

JOSEPH B. TEDROW.
